UNITED STATES PATENT OFFICE.

JEAN ALEXANDRE REY, OF PARIS, FRANCE.

MOORING APPARATUS FOR SUBMARINE MINES.

1,151,903.

Specification of Letters Patent. Patented Aug. 31, 1915.

Application filed June 18, 1913. Serial No. 774,302.

To all whom it may concern:

Be it known that I, JEAN ALEXANDRE REY, a citizen of the French Republic, and residing at 26 Avenue de Suffren, Paris, France, engineer, have invented a new and useful Improvement in Mooring Apparatus for Submarine Mines, which improvement is fully set forth in the following specification.

10 Submarine mines are in existence at the present time in which after immersion of the mine, the lead acting by its own weight upon suitable mechanism, allows the drum upon which the mooring cable is wound, to 60 unwind freely.

15 In order to prevent the drum from unwinding when the anchor or mooring mechanism is raised by a pull upon the cable various arrangements have already 65 been proposed for preventing the lead from coming into action a second time. Before again mooring the mine, it is only necessary again to set the locking mechanism by hand in order to enable the lead line to act.

20 According to the present invention, the arrangement of the apparatus parts is such that the fact of the buoy being or resting upon its anchor or mooring mechanism insures the ability of the lead line to act so as 70 to permit the drum to unwind freely. In the present arrangement, the necessary setting or re-setting of the locking mechanism is effected through the medium of a part which is arranged to be actuated automatically 75 when the buoy is placed on its anchor. This may be accomplished by arranging the part in question at the top portion of the mooring mechanism in such a manner that the buoy, when placed upon its anchor, engages and thereby actuates said part.

25 In the accompanying drawings is illustrated diagrammatically mooring mechanism provided with a typical arrangement of apparatus parts embodying the present 80 invention.

30 In these drawings, Figures 1, 2 and 3 are sectional diametral views of the mechanism showing the different positions of the members during the operation of mooring.

35 Referring to the drawings, *a* is a casing upon which the buoy rests, said casing comprising, with its attached parts, the mine anchor or mooring mechanism. Said casing contains the drum *c* upon which is wound 95 the mooring cable *d* entering the casing

through a suitable aperture in the top thereof. A lead or weight *e*, when not in use, may be carried on a hook *e'*, as shown in Fig. 1. As indicated, the hook is shaped so as readily to release the lead *e* when it is 60 desired to release the latter and permit it to become pendant, as shown in Fig. 2. Said lead is connected by its line *f* to the tail of a pawl *g* or other suitable detent member, provided with a spring *g'* normally tending to draw the tail of the pivoted pawl upward and thereby to force the nose of the pawl into engagement with teeth *h*, arranged on the drum periphery and thus to hold the drum stationary.

70 The weight of the lead is sufficient to overcome the tension of spring *g'*, and the lead therefore operates when pendant, to draw the pawl out of engagement with the drum, except when such movement of the pawl is 75 prevented by suitable locking mechanism of some kind. In the present example, such locking mechanism comprises a bell crank lever *i* pivoted at *i'*, whose upper arm tends to move upwardly, by reason of the tension of spring *j* attached thereto. This arm or lever *i* projects through a hole or slot *k* formed in the setting rod *l* which is vertically movable through a suitable aperture in the top of the casing. The tension of spring *j* is 80 sufficient to draw up lever *i* and also the rod *l*, unless such movement is restrained in some way. The lower arm of bell crank lever *i* is hooked or notched as at *m* to form 85 a latch adapted to engage the tail of the pawl *g*, when the pawl is in locking position and when the latch *m* is swung sufficiently far to the left by operation of the spring *j*. When the latch thus engages 90 the tail of the pawl, the lead line mechanism is thereby locked, as shown in Fig. 3, the lead being now inoperative to release the pawl from its locking engagement with the cable drum, as long as rod *l* remains in its elevated position shown in Fig. 3. The 95 buoy when placed in position upon its anchor presses the rod *l* downwardly as shown in Fig. 1, thereby throwing latch *m* to the right and disengaging the tail of pawl *g*. This places said pawl in readiness to be drawn out of locking engagement with the drum by the lead *e* acting through its line *f*.

100 It may be stated that the buoy and its anchor are usually launched from a vessel or the like when the parts are assembled as 110

shown in Fig. 1. If the lead *e* is suspended from its hook, as shown, it may be released by hand before throwing the mine into the water; or it may be released automatically from the hook by the buoyant action of the water at the moment of launching. Generally, however, the lead is released even before the assemblage has touched the water it being the practice to launch the same from the vessel at a considerable inclination thereto. In either case, the lead becomes pendulous from the tail of the pawl *g* and thereby withdraws the pawl from engagement with the drum to permit free rotation thereof. This permits the anchor to sink freely, the buoy remaining at the surface. As soon as the buoy leaves its anchor, the downward thrust on the setting rod *l* is immediately released. This would at once permit spring *j* to turn bell crank lever *i* about its pivot and throw the latch *m* into its operative position toward the left. It is to be understood that when the latch has assumed this position, if the tension on the lead line has been suddenly reduced, as is the case when the lead strikes bottom, the tension of the spring *g'* is sufficient to draw the pawl tail upward and thereby to move latch *m* slightly to the right against the pressure of spring *j*. When the pawl tail has passed beyond the notch of the latch, the latch is again drawn to the left, thereby preventing any further action of the lead and its line on the pawl, and the cable drum thus being locked against rotation.

Owing to the fact that the lead is apt to oscillate vertically for a few moments after the mine is launched, it is desirable to provide some means to insure that the latch *m* shall not be drawn to the left too soon after the mine is launched, otherwise the oscillations of the lead might so reduce the tension of lead line *f* that the pawl might be drawn upward and be locked prematurely by the latch *m*.

Any suitable means may be provided to guard against this contingency. In the present instance there is provided an arrangement similar to a clock escapement, comprising a series of collars *n* formed on the setting rod *l* with which is adapted to coöperate a crutch device having two arms *o* and *o'*, which are separately rotatable about an axis *p*. One of the arms *o'* for example, is shorter than the other, and the spring *g* tends to draw the arms toward each other. Between the arms is arranged to revolve a suitable cam *r* which is fast with the axle *s* of the drum.

The device just described operates as follows: At the moment of launching the rod *l* having been previously forced down by the buoy into the position illustrated in Fig. 1, is engaged by one or the other of the arms *o*, *o'*. As soon as the mine is launched, the

anchor sinks away from the floating buoy, the cable drum having been released by the lead line mechanism, as described, to permit the cable to be paid out freely. As the drum rotates, the cam *r* acts alternately on the arms *o* and *o'* of the escapement mechanism, the spring *g* at the same time bringing the other arm of the crutch device into engagement with one of the collars *n*. As a consequence, the rod *l* is raised by spring *j* slowly, step by step, the rod attaining its highest position only after a certain number of turns of the drum axle *s*. As a result, the latch *m* does not reach the position shown in Figs. 2 and 3 for some moments after the mine is launched, and by this time the lead *e* has ceased its vertical oscillations and hangs quietly from the tail of the pawl. When the lead touches bottom, the tension on the line *f* ceases and the pawl tail is drawn upwardly, passes the latch *m*, which immediately springs back to prevent the tail being pulled downward again, and the drum is instantly locked against further rotation. All this takes place shortly before the anchor itself reaches the bottom. As no more rope can unwind from the drum, further movement of the mine toward the bottom draws with it the buoy, the buoy or mine being thus anchored permanently a predetermined distance below the surface of the water.

What I claim and desire to secure by Letters-Patent is:

1. Mooring apparatus for submarine mines comprising the combination, with an anchor provided with a rotatable cable drum, detent means arranged when unrestrained to lock said drum, and a pendulous member arranged when pendant to restrain said detent and to hold the same inoperative, of a device arranged to prevent further action of said pendulous means after the drum has become locked, and mechanism for rendering said device inoperative while the anchor is substantially in contact with the buoy with which it is used, said mechanism being arranged to be actuated by bringing such buoy and the anchor substantially into mutual contact.

2. Mooring apparatus for submarine mines comprising the combination with an anchor provided with a rotatable cable drum, detent means arranged when unrestrained to lock said drum, and a pendulous member arranged when pendant to restrain said detent and to hold the same inoperative, of a device arranged to prevent further action of said pendulous means after the drum has become locked, mechanism for rendering said device inoperative while the anchor is substantially in contact with the buoy with which it is used, said mechanism being arranged to be actuated by bringing such buoy and the anchor substantially into mutual con-

tact, and means for insuring operation of said mechanism for a suitable period after separation of the anchor and such buoy.

3. Mooring apparatus for submarine mines comprising the combination, with a buoy, an anchor provided with a rotatable cable drum, and a cable secured to the buoy and passing around said drum, of a detent member adapted to lock the drum against rotation, a weight adapted when freely pendant to hold said detent out of locking position, means arranged to prevent action of said

weight after the drum has once become locked, and an escapement device arranged to restrain such preventing means from operating until after a predetermined number of drum rotations. 15

In testimony whereof I have signed this specification in the presence of two subscribing witnesses.

JEAN ALEXANDRE REY.
